CLAIM

The ornamental design for a vehicle exterior as shown and described.

DESCRIPTION

FIG. 1 is a front, right perspective view of a vehicle exterior, in accordance with an embodiment of our new design; FIG. 2 is a front, right view of the vehicle exterior of FIG. 1;

FIG. 3 is a front view of the vehicle exterior of FIG. 1; FIG. 4 is a rear view of the vehicle exterior of FIG. 1; FIG. 5 is a left view of the vehicle exterior of FIG. 1; FIG. 6 is a right view of the vehicle exterior of FIG. 1; FIG. 7 is a top view of the vehicle exterior of FIG. 1; FIG. 8 is a bottom view of the vehicle exterior of FIG. 1; FIG. 9 is a rear, right view of the vehicle exterior of FIG. 1; FIG. 10 is a front, right perspective view of a vehicle exterior, in accordance with another embodiment of our new design;

FIG. 11 is a front, right view of the vehicle exterior of FIG. 10;

FIG. 12 is a front view of the vehicle exterior of FIG. 10; FIG. 13 is a rear view of the vehicle exterior of FIG. 10; FIG. 14 is a left view of the vehicle exterior of FIG. 10; FIG. 15 is a right view of the vehicle exterior of FIG. 10; FIG. 16 is a top view of the vehicle exterior of FIG. 10; FIG. 17 is a bottom view of the vehicle exterior of FIG. 10; and, FIG. 18 is a rear, right view of the vehicle exterior of FIG. 10.

The ornamental design which is claimed is shown in solid lines in the drawings. The broken lines of equal length dashes in the drawings are for illustrative purposes, depict environmental subject matter, and form no part of the claimed design. Broken lines formed by unequal length

(Continued)

dashes (i.e., dash-dot) define bounds of the claimed design. Diagonal shade lines depict transparent or translucent features of the claimed design.
